CLAIM

The ornamental design for an impeller holding tool, as shown and described.

DESCRIPTION

FIG. 1 is a right side elevational view of an impeller holding tool showing my new design;

FIG. 2 is a rear elevational view;

FIG. 3 is a top plan view;

FIG. 4 is a bottom plan view;

FIG. 5 is a front elevational view;

FIG. 6 is a top, rear and right side perspective view;

FIG. 7 is a right side elevational view of a second embodiment of my new design of FIGS. 1-6, the left side being a mirror image;

FIG. 8 is a bottom plan view of FIG. 7;

FIG. 9 is a right side elevational view of a third embodiment of my new design of FIGS. 1-6, the left side being a mirror image; and,

FIG. 10 is a top plan view of FIG. 9.
